UNITED STATES PATENT OFFICE.

FREDERICK E. HUTCHINGS, OF NEW YORK, N. Y.

FENDER.

1,185,327.

Specification of Letters Patent.

Patented May 30, 1916.

Application filed December 9, 1911. Serial No. 664,819.

To all whom it may concern:

Be it known that I, FREDERICK E. HUTCHINGS, a citizen of the United States, and a resident of the city of New York, borough 5 of Brooklyn, county of Kings, and State of New York, have invented certain new and useful Improvements in Car-Fenders, of which the following is a full, clear, and exact description.

10 This invention relates to certain improvements in fenders or wheel guards designed for use on power driven cars and is equally adaptable to cars driven along predetermined tracks, such as, for instance, electric 15 or cable cars and to dirigible cars such as automobiles, motor trucks, etc.

My invention involves certain improvements in the type of construction, illustrated and claimed in my prior Patent No. 20 1,018,563, granted February 27, 1912, and more particularly involves certain improvements over the second form illustrated but not claimed specifically in said application, and in which the fender body is normally 25 supported in inoperative or raised position and in which a releasing catch may be operated to permit first the lowering and then the forward movement of the fender to operative position. By the term "operative 30 position" I mean in a position to operate as a fender, that is, to receive or engage with the body or obstacle in front of the vehicle, while by the term "inoperative position", I mean in such a position that it 35 will not receive or support a body with which the car may come into collision. The fender shown in my prior patent above referred to, is so supported and so held in its retracted position, that when released it 40 will first drop to the ground before being advanced. The preferred form which my present invention assumes and which is hereinafter described in detail, has substantially the same downwardly and thence forwardly movement, and its lower edge assumes substantially the same three positions, as are illustrated in Figs. 1, 2 and 3 of the said patent.

One object of my present invention is to 50 more effectively support the body of the fender in its raised position, so that there is very little if any liability of the fender body being accidentally or inadvertently dropped.

55 A further object of my invention is to

simplify and render more efficient the means for advancing the fender so that the speed of advancement will be substantially uniform during the entire movement.

A further object of my invention is to 60 provide for the releasing of the fender body by the action of any one of a plurality of hand rails or trips operating independent of each other.

A still further object is to lock the fender 65 against being released while the car is stationary and to automatically free the fender from the locking mechanism as the car starts in motion, so that the fender may then be released by the tripping mechanism. 70

Other objects and advantages of my improved fender will be set forth more fully hereinafter and particularly pointed out in the claims.

Reference is to be had to the accompanying 75 drawings, which form a part of this specification and in which similar reference characters indicate corresponding parts in the different views.

Figure 1 is a side elevation of a front portion of a car and showing in central longitudinal section one embodiment of my invention certain of the parts being shown in tripped position in dotted lines; Fig. 2 is a front view of the car, a portion of the 80 fender body being broken away; and Figs. 3 to 12 inclusive are details of various parts and on a larger scale than Figs. 1 and 2. Fig. 3 is a horizontal section showing the 85 fender retracting drum. Fig. 4 is a vertical section showing the same parts as are shown in Fig. 3 and in the position occupied when the fender is in raised position. Fig. 5 is a view similar to Fig. 4 but showing the 90 parts in the position they occupy when the fender is in lowered position. Fig. 6 is a longitudinal section through one of the side 95 arms, which carry the lower end of the fender body, and showing the fender advancing spring. Fig. 7 is a horizontal section 100 corresponding to Fig. 3, but showing a different fender advancing means. Fig. 8 is a vertical section showing in side elevation a part shown in Fig. 7. Fig. 9 is a side elevation showing the mechanism by which 105 any one of a plurality of hand rails or other trips may each move in any one of the plurality of directions to effect the tripping of the fender body. Fig. 10 is a view similar to Fig. 9, but showing the parts in position 110

after being operated. Fig. 11 is a side elevation of the fender-locking device in operative position. Fig. 12 is a view similar to Fig. 11, but showing the device in inoperative position. Fig. 13 is a sectional detail showing the arms of the hand rails mounted on concentric pivots.

The type of construction illustrated and claimed in my prior application and to which the present invention relates, includes a fender body in the form of a curtain, the lower edge of which is normally supported at some little distance above the ground, but is connected to mechanism whereby upon the tripping of the fender, the said lower edge will be lowered substantially vertically to a position in engagement with or closely adjacent to the ground and may then be advanced substantially horizontally.

In my present construction, I employ a fender body 10 in the form of a flexible curtain. I do not desire to limit myself to any particular form of curtain, as it is evident that the curtain may be formed of canvas, wire netting, pivoted links or any other suitable material. Preferably the lower portion of the curtain is reticulated so as to prevent it from offering any material resistance to the wind and to permit rain or snow to beat through it without collecting on it to any material extent. The upper edge of the curtain is supported on a roller 11, which preferably includes a spring normally tending to wind up the roller. Substantially the same construction might be employed as in the ordinary shade roller and, as such construction forms no part of my invention, it is not thought necessary to illustrate any of the details of the roller. The ends of the roller are supported in arms or hangers 12 depending from and extending outward laterally from the chassis frame. The roller, as well as the curtain, is of sufficient length to extend from the outer side of one front vehicle wheel to the outer side of the other front wheel, and the roller is positioned closely adjacent to the wheels, so as to act not only as an ordinary car fender but also as a wheel guard. The lower edge of the curtain is secured to a transversely extending bar 13, which is somewhat flexible and is comparatively thin at its front edge, so that after the fender body has been dropped and the bar is being advanced, it may slip beneath the person or object which it is desired to pick up, thus serving as a shoe. This shoe is secured to the front ends of two parallel bars or rods 14 which comprise a supporting frame extending substantially horizontally and lengthwise of the car.

In the forms shown in Figs. 1 to 6 inclusive, each bar or rod 14 is formed of two telescoping tube sections 15 and 16, inclosing a coil spring 17 normally tending to extend the bar. In this form, the front end of one

section terminates in a pointed member 18, which is secured to the shoe 13, as is shown in Fig. 1, and the rear end of the outer section is pivotally supported upon a transversely extending shaft 19 on the chassis frame. This shaft carries a drum 20, around which is wound a cable 21, one end being secured to the cable and the other end extending lengthwise through the bar 14 to the front or inner section 16. The spring 17, which is within the bar 14, is held between two stops, one on each section, so that when the cable is wound up on the drum, the inner section will be drawn back into the outer section and a spring 17 will be put under compression. Any suitable means may be employed such, for instance, as a crank for rotating the shaft 19 and winding the cable on the drum. For holding the spring under tension, I provide a ratchet wheel 22 on the shaft 19 and pivotally support a dog 23 adjacent thereto. The dog is connected to a counterbalancing weight 24, which normally holds it in operative engagement with the ratchet wheel, but the dog also has a flange 90 in engagement with the bar 14 a short distance in advance of the shaft 19, so that as the forward end of the bar is lowered, the dog 23 will be pulled out of engagement with the ratchet wheel. As the front end of the bar 14 is raised, the weight 24 will return the dog into operative position. In Fig. 4 I have shown the parts in the position which they normally occupy, while in Fig. 5 I have shown the bar lowered and the ratchet wheel 100 and drum free to rotate. The dog does not release the ratchet wheel until the front end of the bar has lowered into engagement with the ground or to a position closely adjacent thereto, so that when the front end of the bar is released by the mechanism hereinafter described, the shoe 13 will first drop to the ground and the spring 17 will then force the shoe 13 forwardly along the ground.

Instead of forming the bar 14 of a plurality of hollow telescoping sections with the spring inside, I may, if desired, employ the alternative construction illustrated in Figs. 7 and 8. In this form, instead of having a drum on the shaft 19, I employ a pinion 25, which engages with ratchet teeth 26 on the rear end of the bar 14^a. A spring 27 encircles the shaft 19 and has one end secured to the ratchet wheel 22. The same dog 23 and its counterbalancing weight 24 is employed. As the front end of the bar 14^a is dropped, the dog 23 releases the ratchet wheel and the spring 27 causes the shaft 19, the ratchet wheel 22 and the pinion 25 to rotate and advance the bar 14^a. The rear end of the bar is preferably supported in a cradle 28 suspended from the shaft 19, so that the ratchet bar will have proper engagement with the pinion, irrespective of any tilting movement of the bar.

Depending from the front portion of the chassis frame and rigid therewith, are hangers 29, the lower ends of which terminate adjacent to and in the rear of the lower edge 5 of the curtain when the latter is in raised or inoperative position. The bars 14 or the bars 14^a, if the latter be employed, are held against lateral movement by these hangers, as is shown in Fig. 2. Pivoted secured to 10 each hanger 29 is a hook or dog 30, upon which is normally supported the corresponding bar 14. With the hooks or dogs in the position shown in Fig. 2, the bars 14 cannot drop and cannot move laterally and as the 15 dog 23 holds the ratchet wheel 22 at this time, the bars 14 cannot move forwardly. Each dog or hook 30 is in the form of an elbow lever and is connected by a link 31 to a lever 32 rigid on a transversely extending 20 rock shaft 33 supported by the hangers 29 intermediate of the upper and lower ends of the latter. When the rock shaft is oscillated from the position shown in Fig. 9 to the position shown in Fig. 10 by the mechanism 25 hereinafter described, the dogs or hooks 30 will be swung from beneath the bars 14 and the latter will be permitted to drop and the lower edge of the curtain will be shot forward, as hereinbefore described,

30 In Fig. 1 of the drawing I have shown in dotted lines the positions which certain of the parts take in being tripped. The bar 14 first drops to the position 14', at which time the transversely extending bar 13 at 35 the lower edge of the curtain will strike the ground or the track as shown at 13'. The inner member 16 of the bar 14 is then free to move forward as hereinafter more particularly pointed out and the transverse bar 40 13 will slide forward to the position 13'' and the bar 14 will assume the position 14''. I may, if desired, employ means for accelerating the downward movement so that it will not be necessary to rely entirely on 45 gravity. One simple means which might be employed for this purpose is a pivoted lever 34 carried by the hanger 29 and having one end bearing downwardly against the bar 14 and the other end pulled upwardly by a 50 spring 35. One special advantage of this specific construction is that it permits the lever 34 to be swung to a vertical position after the bar 14 is dropped, so that the lever will prevent the shoe 13 from being 55 raised to pass over the person or object which it is desired to pick up in the fender.

The improved fender hereinbefore described may be operated so as to be tripped by the person in control of the car. Preferable it is mounted so as to automatically trip just before the car reaches a person or object in its path. The specific construction illustrated is designed to operate on the same general principle as that disclosed in my 60 prior application previously referred to, but

possesses certain advantages over the prior construction. Each hanger 29 carries two superposed rock shafts or pivots 36 and 37, and upon the outer ends of the two lower rock shafts or pivots 36 are two forwardly 70 and downwardly extending arms 38 connected to a lower transversely extending hand rail 39. From the two upper pivots or rock shafts 37 are two upwardly and forwardly extending arms 40 connected to an upper transversely extending hand rail 41. The arms 38 and 40 may have rearward extensions beyond the pivots if desired, and these may carry counterbalancing weights 42, as shown particularly in Fig. 1. Each 75 lower pivot 36 carries a tumbler 43 in the form of an elbow lever and each upper pivot carries a tumbler 44 normally in engagement with both ends of the adjacent lower tumbler 43. Pivoted to the hanger 29 directly 80 above these tumblers and resting upon the tumbler 44 is a lever 45, which is connected by a link 47 to one of the links 32 on the rock shaft 33.

As previously stated, the fender may be 85 tripped by the rocking of the shaft 33 to lift the links 31 and withdraw the hooks 30. The mechanism last above described serves to raise these links 31 upon an upward or downward movement of either one of the 90 two hand rails 39 and 41 to the positions indicated in dotted lines in Fig. 1 at 39', 39'', 41' and 41''. Normally the parts are disposed substantially as shown in Fig. 9, but if the lower rail 39 be forced downwardly or 95 the upper rail be forced downwardly by contact with another object, the parts will 100 assume the position shown in Fig. 10. This will trip the fender and permit it to be first dropped and then shot forward, as previously described. In case the lower rail should be raised in passing over an object, or if the upper rail be pushed upwardly and backwardly, the tumblers 43 and 44 will be 105 tilted in the opposite direction, but they 110 will operate to raise the lever 45 to the same extent and trip the fender in the same manner. It will be noted that the end of the tumbler away from the pivot of the lever 45 is longer than the end toward the pivot. By 115 forming the parts in this manner, an equal movement of either hand rail in either direction will cause the same upward movement of the lever 45.

It will be noted that the rock shaft 33 extends across the car and is independently connected to both hooks 30 and to both levers 45. Thus, if either lever 45 or either link 46 be broken or displaced or fails to operate the other lever, the corresponding 120 lever or link will cause the proper movement of the rock shaft 33 and both of the hooks 30 will be withdrawn simultaneously.

In order to prevent the fender from being inadvertently tripped while the car is 130

at rest, I provide a locking mechanism shown particularly in Figs. 11 and 12. This locking mechanism includes a lever 47 pivotally supported above the lever 45 and weighted at its upper end. Two stops 48 and 49 are provided so as to limit the movement of the lever. When the lever is swung to a substantially vertical position and in contact with the stop 49, as shown in Fig. 11, its 10 lower end will engage with the upper side of the lever 45 and prevent the latter from being raised. When the lever 45 cannot rise, it is evident that the fender cannot be tripped. When the lever 47 is swung to the 15 position shown in Fig. 12 and in contact with the stop 48, the lever may be lifted and the fender tripped, as hereinbefore described. The lever is swung into the locking position, that is, the position shown in Fig. 20 11, manually, or in any other suitable manner, but it will be noted that the upper end of the lever 47 swings backwardly in traveling to the unlocked position. Thus, with the fender locked, the starting of the car or 25 the jarring of the car will cause the weight constituting the upper end of the lever 47 to automatically swing rearwardly from the position shown in Fig. 11 to the position shown in Fig. 12, and thus automatically 30 unlock the fender and permit it to be operated by a movement of either hand rail.

Various changes may be made in the construction and operation of my improved device within the scope of the appended 35 claims and without departing from the spirit of my invention. For instance, instead of having two tumblers 43 and 44 mounted one above the other, I may mount the arms of the hand rails on concentric 40 pivots, as is shown in Fig. 13. In this figure, the hand rail 38 is mounted on a pivot pin 36^a and the arm 40 is mounted on a sleeve 37^a encircling the pin. Two tumblers 43^a and 44^a are mounted side by side and 45 both in direct engagement with the lever 45, so that by tilting either arm 38 or 40 in either direction, the lever 45 will be raised. This construction permits of the use of a third or even a fourth hand rail, as 50 there may be a plurality of concentric sleeves.

Having thus described my invention, what I claim as new and desire to secure by Letters Patent is:

55 1. A fender including depending hangers adapted to be secured to a car body, a roller supported by said hangers, a curtain wound on said roller, a shoe connected to the free edge of said curtain and normally supported 60 in an elevated position, trip mechanism upon the operation of which said shoe is permitted to drop toward the ground and means for advancing said shoe after the latter has been dropped.

65 2. A fender having a body portion nor-

mally supported in inoperative position, a plurality of separately mounted hand rails disposed in advance of said fender body and movable independently of each other and means for releasing said fender body upon a movement of any one of said hand rails independent of the other. 70

3. A fender having a body normally held in inoperative position, two independent forwardly extending arms and connections 75 between said arms and said fender body, whereby the movement of either arm upwardly or downwardly from a normal position, will release said body and permit it to move to operative position. 80

4. A fender having a fender body, trip mechanism for normally supporting said fender in inoperative position, a rock shaft for operating said trip mechanism, a plurality of hand rails in advance of said fender body and connections between said hand rails and said rock shaft whereby the shaft is oscillated in one direction upon a movement of any one of the hand rails in one of two directions from its normal position. 90

5. A fender including a fender body, side bars for moving the latter to operative position, the rear ends of said bars being pivotally mounted, drums adjacent said rear ends, ratchet wheels adjacent said rear ends, 95 springs normally tending to advance said fender body, cables wound on said drums for retracting said fender body and dogs in engagement with said ratchet wheels for normally preventing the advancement of the 100 fender body and automatically movable to inoperative position upon the lowering of the fender body.

6. A fender having a fender body normally supported in inoperative position, trip mechanism for releasing said fender body, a lock for preventing the operation of said trip mechanism, said lock being automatically moved to inoperative position upon the starting of the vehicle carrying said fender. 105

7. A fender having a body normally supported in inoperative position, trip mechanism for releasing said fender body, a locking member for preventing the operation of said trip mechanism, said locking member comprising a weighted pivoted lever adapted to be automatically displaced from locking position upon the jarring or starting of the vehicle carrying said fender. 115

8. A fender having a roller, a curtain wound thereon, and means for first lowering the free edge of said curtain substantially vertically to the ground and then advancing it to further unwrap the curtain from said roller. 120

9. A fender having a supporting roller, a flexible curtain thereon, a frame pivotally supported at one end and connected to the free edge of said curtain at the opposite end, said frame including telescoping tube sec- 125 130

tions, means for releasing said frame to permit the end connected to said curtain to drop to the ground, means tending to extend said frame and advance the free edge of said curtain, and means for releasing said last mentioned means after said free edge has been lowered a predetermined distance.

10. A fender including depending hangers adapted to be secured to the car body, a roller supported by said hangers, a curtain wound on said roller, a shoe connected with the free edge of said curtain and normally supported in an elevated position, an extensible frame connected to said shoe, trip mechanism for releasing said shoe and permitting it to drop toward the ground in a substantially vertical direction and trip mechanism for permitting the extension of said frame

after a predetermined downward movement of said shoe.

11. A fender having a fender body, means for supporting the same in an elevated position, means normally tending to force said fender body forwardly, means for normally preventing said forward movement, and means for automatically disengaging said last mentioned means after a predetermined lowering movement of the fender body.

In testimony whereof I have signed my name to this specification in the presence of 30 two subscribing witnesses.

FREDERICK E. HUTCHINGS.
